Attorney.

UNITED STATES PATENT OFFICE

PHILIP D. PARSONS, OF SWARTHMORE, PENNSYLVANIA, ASSIGNOR TO SCOTT PAPER COMPANY, A CORPORATION OF PENNSYLVANIA

CORE STRUCTURE FOR PAPER ROLLS

Application filed October 1, 1930. Serial No. 485,810.

Heretofore it has been the practice in paper making to wind the web leaving the last drying cylinder of a paper making machine into a large roll upon a central bore or cylinder having extended ends constituting journals, subsequently severing the paper web and starting it to wind upon a second core or cylinder, and at this time transferring the fully wound paper roll to a separate machine for slitting and rewinding; and during the rewinding operation, trimming and slitting the web into desired widths of roll for subsequent treatment in making articles such as towels and napkins, for example; and further, during the transfer and rewinding of the paper roll, separately transferring the new roll being wound with the paper from the drying cylinders to the journal supports formerly employed for the paper roll which is transferred to the trimming, slitting and rewinding machine, and thereafter repeating the operation.

This application is, in part, a continuing application of my application Serial No. 78,743, filed January 2, 1926 and which in turn is a division of my application Serial No. 730,830, filed August 8, 1924 which was issued as Patent Number 1,759,627, dated May 20, 1930. The present application is especially directed to the structure of divided core and mandrel adapted as a composite drum for use where it is desired to divide and wind a web of paper into a plurality of paper rolls each provided with a metal or other core of proper length and suitable for further handling of the paper in slitting and rewinding machines.

As a particular use of the divided core drum and mandrel of the present application, I have described in my application Serial No. 78,743, its adaptability for use in connection with what is known as a Pope winding reel, set out in Letters Patent 1,248,542 of December 4, 1917; but I do not restrict the use of my invention to that type of winding machine, as it is adapted to various types of the slitting and rewinding machines already in use.

Referring to the drawings; Fig. 1 is a side view illustrating, diagrammatically, the

manner in which the paper web may be slit and wound upon the divided tubular core and mandrel; Fig. 2 is a plan view of the same; Fig. 3 is a plan view (partly in section) of my improved divided tubular core and mandrel forming a composite drum upon which the split web is to be wound; and Fig. 4 is a side view of one of the clamping collars.

Referring to Figs. 1 and 2, the paper web P may be slit along lines 5 and 5a by means of disc cutters 7 and 7a of any suitable construction arranged upon a rotating shaft 7b and cooperating with a slitting cylinder 7d adapted to rotate in slitting relation to the cutters. 3 is a revolving drum upon which the paper rolls H on the divided tubular core and mandrel 12 press and by which they are caused to rotate at a surface speed commensurate with the speed of the drum 3.

The construction of the winding drum 12 and its associated parts are best shown in Fig. 3, from which it will be seen that the mandrel shaft 13 is provided at each end with a box 14 in which it is journalled and by which it is supported in the ends of the radial arms 16. The mandrel shaft is provided with collars 13a by which the positions of the journal boxes are assured and these boxes may, if desired, be of a size which will permit them being drawn through the tube sections 12a and 12b forming the drum 12.

If desired, the journal boxes 14 may be removable from the shaft 13 when it is desired to separate the rolls of paper, each associated with its respective tubular core 12a and 12b. It will be further seen that the shaft 13 is provided with plug portions 24 and 25 over and upon which the tubular core parts 12a and 12b are arranged and supported when acting as a drum; the plug 25 being preferably longer than the plugs 24 as it supports the abutting ends of the two tubular core portions 12a and 12b.

Near one end of the shaft 13 and adjacent to one of the end plugs 24 thereon, is a collar 26 secured to the shaft 13; and at the other end between the other end plug 24 and the shaft bearing 14, there is arranged a second collar 27 and a locking nut 28 screwed upon the shaft. The collar 27 may be slotted, as

at 27a (Fig. 4), and may be slipped over the shaft 13 before being clamped against the end of the tubular core 12a by the nut 28. When this has been done, the tube section 12b is 5 clamped against the collar 26 while the tube section 12a is tightly abutted at 12c against the end of the tube section 12b; and at the same time, the collar 27 and nut 28 are the clamping means for the other and outer end 10 of the tube section 12a.

After the paper webs are wound upon these tube sections 12a and 12b, they, together with the tubes acting as cores, should be separated from the mandrel shaft 13 and its plugs and 15 collars, the said cores remaining with the paper rolls and providing definite means of support for the rolls, when they are subjected to further treatment in other machines, such for example as being slit, transversely perforated and rewound into small commercial toilet paper rolls.

To accomplish this operation, the nut 28 is loosened, the collar 27 is withdrawn, and the shaft, together with the collar 26, its plugs 24 25 and 25, and nut 28, with or without its bearing 14, are withdrawn through the tube sections 12a and 12b. When this mandrel portion of the equipment is withdrawn, the tubes will be entirely free to separate and each roll 30 will have its own tube or core.

As it is desirable to trim the side edges of the paper web P, the slitting cutters 7a provide the slit portions 5a, these lines of slitting being in alignment with the outer ends of the 35 respective tube sections 12a and 12b, the narrow rolls formed outside of the line of slitting 5a being waste. It will be understood that this trimmed waste may be discarded at once when the trimming has taken place.

40 While I have shown the drum 12 divided into two abutting tubular portions, I do not restrict myself in this particular, as it is manifest that the drum may be composed of two or more tubular sections as desired.

45 While the special construction of the drum 12 is adapted for use in connection with different types of machines, I have, by way of example, illustrated it in respect to its use in what is commercially known as a "Pope reel".

50 Referring to Figs. 1 and 2, it will be observed that the journal boxes 14 of the mandrel shaft 13 are supported in notched portions 15 of a pivoted frame 16 pivoted to move about an axis 17 under the action of a curved rack 16a and pinion 19 on a rotatable shaft 20 having a hand wheel 20a by which to rotate it.

After the paper web is slit and partly wound upon the winding drum 12, and after the paper web is severed from the paper roll 60 H at the rear of the machine, said roll H may be removed and the radial arms 21 which formerly supported it may be adjusted toward the revolving drum 3 in such position as to receive the shaft or mandrel 13 of the drum carried by the pivoted frame 16 when

said frame is oscillated toward the said arms 21 whereby it is received by the open ends of said frame and after which, the slit paper web is caused to continue to be wound upon the drum until a large roll is formed as shown 70 at H; thereafter, a new drum 12 is placed in position upon the frame 16, the paper web broken from the full roll H and attached to the drum to start a new roll. The rolls so formed are subsequently disconnected by the 75 removal of the mandrel 13 and permitting the core sections with their individual paper rolls to be separated as before described.

It will now be apparent that I have devised a novel and useful construction and method 80 of operation thereof which embodies the features of advantage enumerated as desirable, and while I have in the present instance shown and described the preferred embodiment thereof which has been found in practice to give satisfactory and reliable results, it is to be understood that I do not restrict myself to the details stated as the same are susceptible of modification in various particulars, without departing from the spirit 85 or scope of the invention.

I claim:

1. A core structure constituting a drum for use in paper slitting and winding machines comprising a plurality of tubular core parts 95 arranged end to end in abutting axial alignment and having their abutting portions positioned in exact transverse circumferential alignment with the slit portions of the paper web being slit and wound, said abutting ends of the core parts being within a plane in which the abutting ends of the core parts and paper roll ends terminate so that the abutting core ends extend exactly in the plane of the slit ends of the paper roll, a 100 shaft extending through the tubular core parts and having its respective ends provided with journals, and centralizing plugs upon the shaft of the same external diameter as the tubular opening in the core parts and in 105 transverse alignment with the abutting ends thereof for supporting the said tubular core parts in axial alignment with each other and with the shaft.

2. The invention according to claim 1, 115 wherein further, the shaft is provided with collars arranged to clamp the tubular cores in an end to end alignment, one of said collars being detachable, and journal bearings for the journals of the shaft and detachable 120 therefrom.

In testimony of which invention, I hereunto set my hand.

PHILIP D. PARSONS
